UNITED STATES PATENT OFFICE.

CHARLES W. McCORMICK, OF EMPORIA, KANSAS, ASSIGNOR TO LAMSON
CONSOLIDATED STORE SERVICE COMPANY, OF NEWARK, NEW JERSEY,
A CORPORATION OF NEW JERSEY.

STORE-SERVICE APPARATUS.

No. 800,666.

Specification of Letters Patent.

Patented Oct. 3, 1905.

Application filed April 2, 1903. Serial No. 150,776.

To all whom it may concern:

Be it known that I, CHARLES W. McCORMICK, of Emporia, in the county of Lyon and State of Kansas, have invented certain new and 5 useful Improvements in Store-Service Apparatus, of which the following is a specification.

My invention relates to new and useful improvements in idlers for cable-carrier apparatus; and the object is to produce an idler 10 which may be set at any desired position to allow the travel of the cable-cord in any direction.

My invention consists of certain novel features hereinafter described, and particularly 15 pointed out in the claims.

In the accompanying drawings, which illustrate a construction embodying my invention, Figure 1 shows an idler suspended from the ceiling in position to support a cord running 20 along the ceiling. Fig. 2 is a side elevation of the same. Fig. 3 is a cross-sectional view on the line α α , Fig. 2. Fig. 4 shows an idler supported on the side wall with the cable passing over pulleys with the guard on the idler 25 adjusted in proper position. Fig. 5 shows the idler supported on the floor with another one of its adjusted positions in dotted lines, the object being to pass the cord or cable upward or downward at an angle.

Like letters of reference refer to like parts 30 throughout the several views.

Secured to the support A, which may be either the ceiling, wall, or floor, is the bracket B, having its extremity bifurcated. Adjustably mounted on the bracket is the U-shaped 35 frame D by means of the bolt C, passing through a lug on said frame and the bifurcated end of the bracket. By means of the bolt the frame can be secured in its adjustment on the 40 bracket.

In the arms of the frame D are seated the opposite bearings E, arranged in pairs. In each pair of bearings is journaled the shaft of the grooved wheel F, over which the cord G' 45 travels, as shown in Fig. 4. The inner ends of the bearings E project from the inner sides of the arms D and mounted on the same is the guard G. The latter is bail-shaped and its ends are split collars which are clamped on 50 the ends of the bearings by screws passing

through the members forming the collars. By loosening and tightening these screws the guard can be adjusted relatively to the cable-cord.

In the art of store-service, especially the sub-class known as "cable-carriers," it sometimes occurs that the merchant objects to the motor and the counter-shaft being placed under the cashier's desk. In instances of this kind it has been found necessary to lead the cable 60 some distance to the engine-room, which has given rise to the necessity of providing an idler which may be set in any position to allow the travel of the cable-cord in any direction. The adjustability of the guard G to the 65 cable-cord is of great advantage, as it can be adjusted to any desired position to offer the greatest safety to the cord G' from jumping off the pulleys F.

I do not limit myself to the arrangement 70 and construction shown, as the same may be varied without departing from the spirit of my invention.

Having thus described the nature of my invention and set forth a construction embodying the same, what I claim as new, and desire to secure by Letters Patent of the United States, is—

1. In a store-service apparatus, a bracket, a frame on said bracket and having arms, opposite bearings seated in said arms, a shaft journaled in said bearings, a wheel on said shaft, and a guard adjustably mounted on said bearings.

2. In a store-service apparatus, a bracket, a frame having arms pivoted to said bracket, opposite bearings seated in said arms and projecting inwardly from the same, a shaft journaled in said bearings, a wheel on said shaft, and a guard having split collars at its ends 85 clamped on the projecting ends of said bearings.

In testimony whereof I have signed my name to this specification, in the presence of two subscribing witnesses, this 16th day of January, 95 A. D. 1903.

CHARLES W. McCORMICK.
